UNITED STATES PATENT OFFICE.

JAMES SMITH STOCKMAN, OF BROOKLYN, NEW YORK.

MEANS FOR CHOCKING AND STARTING LIFE-BOATS, &c.

1,275,101.

Specification of Letters Patent.

Patented Aug. 6, 1918.

Application filed May 6, 1918. Serial No. 232,821.

To all whom it may concern:

Be it known that I, JAMES SMITH STOCKMAN, a subject of the King of Great Britain, having declared my intention of becoming a citizen of the United States, and a resident of the borough of Brooklyn, county of Kings, city and State of New York, have invented certain new and useful Improvements in Means for Chocking and Starting 5 Life-Boats, &c., of which the following is a specification.

While applicable to other objects and purposes, my improvements are designed more particularly for use as a means for mounting life and other auxiliary boats on the decks of ships or other supports in such manner that in emergency such boats may be quickly and conveniently raised and manipulated for the purpose of casting off, as 10 hereinafter more fully set forth. The invention consists in the specific construction, combination, and arrangement of parts described and claimed,—a distinctive feature being the supporting of the keel of the boat 15 fore and aft on bearing rollers mounted on rocker arms which may be raised by leverage applied adjacent to their fulcrums, whereby the inertness of rest is readily overcome and an initial speed of motion 20 imparted that aids materially in raising the boat and its keel clear of the chocks and starting the boat upward,—thereby relieving the tackle and fall of the initial strain heretofore and otherwise involved, and obviating the need of a number of extra hands 25 to effect the starting or lifting of the boat as a preliminary to hoisting and casting off in the usual manner.

In the accompanying drawings, 40 Figure 1, is a diagrammatic representation illustrating symbolically a practical application of my invention;

Fig. 2, is a plan of one of my combined boat chocks and starters;

Fig. 3, is a side elevation of the same, with the starter raised;

Fig. 4, is a substantially central longitudinal section through Fig. 2;

Fig. 5, is a similar longitudinal section, 50 with the starter raised;

Fig. 6, is an end view of my starter-chock;

Fig. 7, is a section taken upon plane of line 7—7, Fig. 5.

Fig. 1, illustrates diagrammatically the 55 use of my starter-chocks S, S, in maintaining a boat B, on a deck, or other support,—T, T, representing the usual davits and tackle and fall provided for the hoisting and lowering of the boat when required.

The operative parts of my starter-chock S, are assembled upon and mainly between parallel uprights or standards s, s of the chock base s', which is adapted to be rigidly secured to a fixed support. Said base 65 s, is formed with a chock rest s², for the support of the starting roller r, when the latter is in lowered normal position as shown in solid lines in Figs. 2, 4 and 6, and in dotted lines in Figs. 3 and 5.

As shown in the drawings the starting roller r, is mounted upon an axle a, extending between and rigidly attached to the rocker arms a', a², although this is not essential, as the roller may be rotatably 75 mounted in any other way, as may be found most expedient. In fact, for that matter, the roller r, may be omitted, and a convexly curved bearing surface substituted in lieu thereof for contact with the keel b, 80 (represented by the lines b², in all but Fig. 1) of the boat B, although the roller is obviously preferable as a means of reducing frictional contact with the keel and insuring easy riding thereunder. The rocker 85 arms a', a², are pivotally supported on an axle or trunnions a³, mounted on and between the uprights s, s, to which axle they may be rigidly attached, as well as being rigidly secured to the segmental gear a⁴, positioned 90 between them, so that the said arms a', a², are under the control of said segmental gear a⁴, as will be understood by reference particularly to Figs. 4 and 5.

Meshing with the segmental gear a⁴, is a 95 power pinion p, rigidly secured to a shaft p', mounted upon and between the standards s, s, of the base s', and protruding beyond standards on one or both sides of the starter-chock S, considered as a whole. A 100 lever L, is either permanently or temporarily attached to the power shaft p', by any well-known mechanical expedient, and is used to actuate the power pinion p, and seg-

mental gear a^4 , upon occasion to raise the rocker arms a' , a^2 , and roller r .

The power shaft p' , may be extended beyond the starter-chock S , sufficiently to enable the actuating lever L , to clear the beam of the boat B , so as to facilitate manipulation.

The roller r , is formed on its inner side with a flange r' , for guiding and retaining contact with the keel b , of the boat B , but its other side is unflanged, and preferably flush with the adjacent edge of the rocker arm a^2 , as shown particularly in Fig. 7, so as to facilitate the release of the keel of the boat when the rocker arms are manipulated to raise the roller above the standards s , s , as in Figs. 3 and 5.

Both bow and stern starter-chocks S , S , are of like construction, being reversed only as related to each other, and having their levers L , L , extending in opposite directions as shown in Fig. 1, in which M , represents the medial chock usually provided for the purpose of sustaining the boat laterally.

By means of my starter-chocks a boat may be quickly and easily loosened up and its keel cleared so as to facilitate and expedite hoisting by means of the usual fall and tackle—the relatively great power that may be applied for the purpose through the medium of the levers L , L , overcoming the dead weight or inertia of the boat at rest, and obviating the necessity for the employment of extra hands and help for the purpose, since a man to each lever and a man to each fall to take in slack is sufficient to accomplish the preliminary raising and starting of the boat in a satisfactory manner. Furthermore the "hoist" is clean and clear because the proper alinement of the boat is not disturbed nor impaired by extra hands heretofore indispensable to start the lift of the dead weight of the boat.

My invention is of especial importance under present war conditions, as in case of emergency it will save much valuable time and labor, and prevent crowding and confusion when life boats and similar craft are desired for immediate use.

It will be noted that my device embodies practically and essentially a combination of chock and starting mechanism, and hence I designate it herein as a starter-chock as it performs both functions, as hereinbefore set forth.

I have herein shown and described my keel-bearing roller as mounted on and between two rocker arms, although it is obvious that it might be mounted on one rocker arm with like result if said rocker arm were made of sufficient strength for the purpose. It is also obvious that the chock seat s' , might be omitted without departing from the spirit and intent of my invention, since the rocker arms a' , might rest directly upon the base s' ,

but said chock seat is desirable in that it reinforces the roller r , and sustains it against the weight exerted through the keel of the boat.

What I claim as my invention and desire to secure by Letters Patent is,

1. A starter-chock of the character designated, comprising a base formed with a chock seat, a keel bearing roller adapted to rest directly upon said chock seat and mounted on a rocker arm, said rocker arm, and mechanism for positively raising said rocker arm and keel bearing roller, for the purpose described.

2. A starter-chock of the character designated, comprising a base formed with a chock seat, a keel bearing roller adapted to rest directly upon said chock seat and mounted on a rocker arm, said rocker arm, a gear pivotally and rigidly attached thereto, a power pinion meshing with said gear, and mechanical means for actuating said power pinion, for the purpose described.

3. A starter-chock of the character designated, comprising a base formed with a chock seat, a keel bearing adapted to rest directly upon said chock seat and mounted on rocker arms, said rocker arms, and mechanism for positively raising said rocker arms and keel bearing, for the purpose described.

4. A starter-chock of the character designated, comprising a base formed with a chock seat, a keel bearing roller adapted to rest directly upon said chock seat and mounted on and between rocker arms, said rocker arms, and mechanism for positively raising said rocker arms and keel bearing, for the purpose described.

5. A starter-chock of the character designated, comprising a base formed with a chock seat, a keel bearing roller adapted to rest directly upon said chock seat and mounted on and between rocker arms, said rocker arms, a gear rigidly attached thereto, a power pinion meshing with said gear, and mechanical means for actuating said power pinion, for the purpose described.

6. A starter-chock of the character designated, comprising a base formed with a chock-seat, a keel bearing adapted to rest directly upon said chock-seat, a pivoted support for said bearing, and means for positively raising said bearing and support.

7. A starter-chock of the character designated, comprising a base with chock-seat, a keel roller and rocker arms, said roller adapted to rest directly upon said chock-seat and mechanism for positively raising said roller and rocker arms, for the purpose described.

8. A starter-chock of the character designated, comprising a base formed with a chock rest, a keel bearing roller adapted to rest directly upon said chock seat and mounted on and between rocker arms, said rocker

arms, a segmental gear between said rocker arms and rigidly attached thereto, a power pinion meshing with said segmental gear, and a lever arranged to actuate said power pinion, for the purpose described.

9. A starter-chock of the character designated, comprising a base formed with a chock rest and a medial shock, rocker arms

mounted in the sides of said base, a power shaft, a lever on said shaft, and a gear on the shaft of said rocker arms and controlling the latter.

JAMES SMITH STOCKMAN.
